UNITED STATES PATENT OFFICE.

CHARLES F. ESTWICK, OF ROCHESTER, NEW YORK, ASSIGNOR TO GENERAL RAILWAY SIGNAL COMPANY, OF ROCHESTER, NEW YORK.

TRAIN CONTROL.

Application filed September 29, 1923. Serial No. 663,819.

This invention relates to automatic train control systems, and particularly to the type of systems in which continuous inductive influences are transmitted to suitable car-
5 carried train control apparatus to maintain them in their normal inactive condition.

In a certain kind of train control system of the continuous inductive type, a two-element or polyphase relay is provided on 10 the railway vehicle which may be energized to produce a torque in one direction or the other, or may be deenergized. In the particular type of system referred to, the flow of alternating current in the usual track circuit ahead of the train (conveniently called the loop circuit), is detected and amplified and is applied to one of the windings of the relay; and current flowing in the two rails in multiple (conveniently called a simplex circuit), is detected and amplified and applied to the other winding of the relay. In such a system, a certain amount of phase displacement between the two currents is necessary to make the relay operate; and if the instantaneous polarity of one of the currents is reversed, the relay will operate in the reverse direction. In other words, a certain phase relation between the currents in the two circuits is necessary in order to energize the car-carried relay when it should be energized, and conversely, an improper phase relation between these two currents may cause a false energization of this relay. In 30 a train control system of this kind, a variation and changing in the phase relation of the several currents mentioned is very likely.

This is especially true of the loop circuit current on account of the variable ballast resistance which changes the value and phase 40 relation of the current shunted by the train and detected, amplified and applied to the relay.

In applying the principle of continuous inductive control to a train control system in which the track rails themselves are used to carry the signaling current and where 45 alternating current is used for propulsion purposes which also returns through the track rails, it is found that under certain 50 distribution of the propulsion current between the two track rails this propulsion current may falsely energize the car-carried relay, even though the frequency of the propulsion current is widely different from the 55 frequency of the signaling current. Obvi-

ously, this is very undesirable because such energization of the car-carried relay might occur at a time when it should not be energized and would constitute a false clear or 60 caution indication.

With the above and other considerations in mind, it is proposed in accordance with the present invention to provide two car-carried relays, one of which is energized by reason of the presence of current flowing in 65 the loop circuit ahead of the train, and the other one of which is energized by the flow of simplex circuit current flowing in the two rails in multiple, the car-carried and track-way apparatus being designed so that the 70 simplex current is normally of a much smaller value than is the loop circuit current, and the car-carried relay responsive to simplex circuit current is correspondingly more sensitive than is the other relay. With 75 this proportioning of the two currents flowing in the simplex and loop circuits, respectively, the relay connected to be responsive to loop circuit current could not be picked up by simplex circuit current, even though 80 (due to bad bonding or the like) most of the simplex current were flowing in one of the rails, for the reason that the simplex current is considerably smaller than is the loop circuit current and is not large enough 85 to pick up the loop circuit relay. Also, the relay connected to be responsive to simplex current could not respond to loop circuit current, because the detecting apparatus for the simplex current is located a considerable 90 distance in the rear of the first few axles of the train so that the loop circuit current is shunted away from this detecting apparatus. As a further assurance that one of these relays will not be picked up by current 95 intended to operate the other relay, these 100 relays and associated circuits may be tuned to respond to currents of different frequencies, and the loop and simplex circuits may similarly be supplied with currents of different frequencies.

As a further object of the present invention, it is proposed to employ in those systems in which alternating current is used for propulsion purposes, means for tuning 105 the car-carried influence detecting apparatus to readily respond to the signaling current but not readily respond to the propulsion current, it being assumed that these two currents are of widely different fre- 110

quencies. More specifically, it is proposed to provide either a shunting circuit or wave filter, so to speak, which is tuned for the propulsion current so that any current of the frequency used for propulsion purposes flowing in the car-carried apparatus may flow without producing any detrimental effects upon the relays by leaking through such a shunting circuit, or to provide a barrier for currents of a frequency close to that of the propulsion current so that these currents can not readily flow in the receiving apparatus.

As a still further object of the present invention, it is proposed to arrange the trackway apparatus so that an indication may be obtained, due to the absence of loop circuit current without actually cutting this current entirely off of the track circuit, but effectively cutting it off as far as the car-carried influence receiving apparatus is concerned. In the proposed system, one indication may be obtained by having two relays energized, a second indication may be obtained by having the loop circuit relay only energized, a third indication by having the simplex relay only energized because the source of energy feeding a certain track section is connected to the entrance end of the section, so that the current in the track rails does not flow ahead of the train, and a fourth indication by having both of these relays deenergized.

Other objects, purposes, and characteristic features of the invention will appear as the description thereof progresses.

In describing the invention in detail, reference will be made to the accompanying drawings, in which:—

Figure 1 illustrates conventionally and in a diagrammatic manner the essential elements of the car-carried and trackway apparatus of a system embodying the present invention; and

Fig. 2 illustrates the transformers and transmission lines of a system, such as shown in Fig. 1, but employing signaling currents of two different frequencies instead of one frequency, as shown in Fig. 1.

Trackway apparatus.—In describing the particular embodiment of the invention illustrated in Fig. 1, the trackway apparatus and circuits will first be described, after which the car-carried apparatus will be described in detail and the operation of the system will be taken up. Although the train control system embodying this invention may be applied to any type of signaling system, such as manual, semi-automatic or automatic block signal systems, using either alternating current or direct current track circuits, for convenience automatic block signal territory employing alternating current track circuits only has been illustrated.

The reference character 1 designates the

usual track rails divided by insulated joints 2 into blocks, the block I and the adjacent ends of two other blocks H and J having been shown. Since the trackway devices and circuits of the several blocks are the same, they are given the same reference characters with distinctive exponents. Each of the blocks is divided into two parts by insulating joints 3, the first part of which may conveniently be called the first 75 or rear section and the second part the second or advance section of the block, the point D designating the junction of these two sections. The first section of each block is provided with the usual track relay 80 T, whereas a track relay U is provided near the middle part of the second section of each block.

As the present invention is particularly applicable to roads employing electric propulsion currents the insulating joints 2 and 3 have been shown in one of the track rails only, the other track rail acting as a return for the propulsion current.

At the entrance to each block is provided the usual type of wayside signal, which may either be a position light, a distinctive aspect color light, or a semaphore signal, and for convenience semaphore signals Z have been illustrated conventionally without showing their well-known operating mechanism and the control circuits, it being understood that each of these signals will indicate stop when the block at the entrance to which they are placed is occupied, or presents dangerous conditions for some other reason, will indicate caution when the next block in advance is occupied, and will indicate clear when both of these blocks are unoccupied as well understood by those skilled 100 in the art of railway signaling.

A suitable transmission line comprising the wires 4 is provided along the trackway in any suitable manner for supplying the usual signaling current, which may be of a 110 commercial frequency, such as 60 cycles, or may be of a special and probably higher frequency. The exit end of the first section of each block is provided with track circuit current derived from a transformer 5, providing the second section of this block is clear. The circuit for supplying this track circuit current may be readily traced on the drawings, and includes the usual track circuit impedance 6 and the front contact 7 of 120 the track relay U of the second section of the block, so that the first section of the block is supplied with trackway energy only if the second section of the block is unoccupied.

The exit end of the second section of the block I is connected to a source to allow alternating current of a predetermined polarity with respect to the alternating source to flow when the block next in advance is clear. 130

The circuit for supplying this energy may be traced as follows:—beginning at the secondary winding of the transformer 8, wire 9, front contact 10¹ of the track relay T¹, wire 11, one of the track rails of the second section, wire 12, winding of the track relay U, wire 13, the other rail of the trackway, wire 14, front contact 15¹, wire 16, track impedance 17 back to the secondary winding of the transformer 8.

With the block J occupied and the track relay T¹ deenergized, this second section of the block I is energized from the rear or entrance end of this section by current having the same relative polarity through a circuit which may be traced as follows:—beginning at the secondary winding of the transformer 8, wire 9, contact 10¹ in its lower position, wire 18, track rail of the second section of the block I, wire 12, winding of the track relay U, wire 13, through the other track rail, wire 19, contact 15¹ in its lower position, wire 16, track circuit impedance 17 back to the secondary winding of the transformer 8.

It should be noted that the changing of the feed from the exit end to the entrance end of the second section of the block I does not change the operation of the signaling system, because the track relay U functions equally as well if the source of energy is at one end of the section as when it is at the other end of the section, assuming that this relay is located substantially at the midpoint of this section. It may be pointed out at this time that under certain atmospheric and ballast conditions, it may be necessary to provide two relays instead of the track relay U, that is, one near each end of this section in order to cause proper shunting of at least one relay due to the presence of a train in this section. The track feed is changed from the exit end to the entrance end of a section of a block, so that the trackway current may not be detected by suitable detecting or influence receiving elements located in front of the front axle of the train when the train is moving in the normal direction of traffic, as indicated by the arrow and as more clearly described hereinafter.

In other words, if a train, moving in the normal direction of traffic, is passing over the second section and the energy is supplied from the exit end of this section, the bulk of the trackway current will flow through the first axles of the train and may be detected by the influence receiving means; whereas if this section of the trackway has its track feed at the entrance end to this section, the track circuit current will be shunted through various axles in the rear part of the train and, therefore, the current flowing will not affect the influence receiving means lo-

cated in front of the first axle, as more clearly described hereinafter.

The trackway apparatus thus far described includes the devices necessary to control the various track relays T and U and the signals Z. In addition to these circuits and devices, there is provided means for conducting current through the two rails in multiple, which for convenience will be referred to as the simplex circuit current hereinafter. In the first section of the block I, this simplex circuit current is only flowing when the next block in advance (block J) is clear and flows through the following circuit:—beginning at the secondary winding of the transformer 20, wire 21, front contact 22¹, wire 23 to the middle point of the balancing resistance 24, where the current divides between the two track rails 1 of the first section of the block I to the middle point of the balancing resistance 25 located at the exit end of this section, wire 26 back to the secondary winding of the transformer 20. Obviously, if the block next in advance is occupied, the first section of a block in question is deprived of the simplex circuit current and the car-carried apparatus will respond accordingly.

The second section of the block I is provided with simplex circuit current in a manner as readily seen from the drawings by means comprising balancing resistances 27 and 28, having their midpoints connected to the secondary winding of a transformer 29, and balancing resistances 42 and 43 having their midpoints connected to the secondary winding of the transformer 44 through the front contact 51¹ of the track relay T¹.

By studying the arrangement of trackway devices as shown in Fig. 1, it will be noted that the first section of any block is deprived of simplex circuit current when the next block in advance is occupied, because the front contact 22 of the track relay T of the advance block is open, thus interrupting the simplex circuit of the first section of the block in question; and that the second section of a block has its trackway circuit feed changed from the exit end of this section to the entrance end of this section when the block next in advance becomes occupied, and further has the simplex current cut off at the extreme exit end so that simplex circuit current only may be detected at the first part of the second section, and neither loop nor simplex circuit current may be detected near the exit end of this second section. That is, a train moving from left to right in the direction of the arrow through a block when the next block in advance is occupied is deprived of simplex circuit current in the first section, is deprived of loop circuit current in the first part of the second section of the

block, and is deprived of both loop and simplex current at the exit end of this second section under these traffic conditions, for reasons heretofore explained.

5 An alternating propulsion current is supplied by a generator AC which is connected in any suitable manner between one of the track rails and a suitable wayside conductor such as a trolley wire or third rail, represented in the drawings as the trolley wire 80.

Car-carried apparatus.—For convenience, a railway vehicle has been conventionally shown by the first and last axles 30 and 31, respectively, of an engine and tender unit, 15 or a car of a multiple unit electric train, dependent upon the type of system to which the train control system is applied. The propulsion current is conducted from the trolley wire 80 to the motors and other car 20 apparatus by means of a trolley 81, a showing of the particular car-carried motors and equipment being omitted to simplify the disclosure. Directly in front of the first axle 30 is provided a suitable influence detecting or receiving element LE for detecting the flow of alternating current in one direction through one of the rails, and in the other direction through the other rail (loop circuit current). This loop circuit 25 influence receiving element LE comprises a core 32 of suitable magnetic material, preferably laminated, insulated between the lamina and supported a suitable clearing distance above the track rails. This core 32 30 has depending legs and pole pieces 33, 34 and 35, and is provided with coils 36 and 37 connected in series so that current flowing in one direction in one rail through the axles of the vehicle and back in the other 35 direction through the other rail will induce electro-motive-forces in the windings 36 and 37 which are cumulative. Similarly, a simplex influence receiving car element SE for detecting current flowing through the two 40 rails in multiple (simplex circuit current) is provided in the rear of the axle 31. This element SE comprises a similar core 38 having depending legs and pole pieces 39 and 40, respectively, and is provided with a 45 winding 41 in which electro-motive-forces are induced due to currents flowing in the same direction in the two rails in multiple.

The loop circuit current influence detecting element LE is connected to a loop circuit amplifying device, conventionally designated by a square AL. This amplifying device AL is connected to a relay L, and is so designed that the currents flowing in the loop circuit ahead of the train are detected and 55 amplified and applied to the relay L to control the same. The amplifying device AL and the relay L are designed to function to operate suitable contacts dependent upon the flow of current in the loop circuit ahead 60 of the train. This may be accomplished by

merely amplifying the current by suitable vacuum tube thermionic amplifiers and by constructing the relay L to function on alternating current, or by constructing the device AL to both amplify and rectify the 70 current detected, and construct the relay L to function on direct current. The simplex amplifying device AS and the simplex relay S are preferably constructed similar to the devices AL and L just described, but 75 preferably respond to a current of a smaller value than do the devices AL and L.

As heretofore mentioned, in certain types of railway systems the cars and locomotive are propelled by electric current, either direct or alternating; and in order to make the train control system immune to the flow of alternating propulsion current in the track-way, suitable tuning devices are preferably provided so as to permit the signaling current 80 to pass freely which signaling current may be assumed to be of 60 cycles, and will readily cause the relay L or S, as the case may be, to respond; whereas the flow of propulsion current, which may be assumed 85 to be of 25 cycles, will not readily find its way through the amplifying devices to operate the relays L and S. Two such tuning devices M and N have been illustrated in the simplex circuit and the loop circuit, 90 respectively. It should, however, be understood that either of the tuning devices M and N may be used in both of these circuits, if desired. In order to impress a maximum voltage on the amplifying device AS as a 95 result of current flowing in the influence receiving element SE, a condenser 47 is connected in series therewith which is of a size to cause potential resonance, that is, produce a maximum voltage across this condenser 100 47, and consequently across the amplifying device AS.

The tuning device M is connected in multiple with the lead wires coming from the simplex element SE. This tuning device M 110 comprises an inductance 45 connected in series with a condenser 46. This inductance 45 and condenser 46 are of such capacity that they resonate at the frequency of the propulsion current, that is, this device is 115 tuned for resonance at the frequency of the propulsion current so that this device offers low impedance and practically forms a shunt for propulsion current frequency detected by the influence receiving element SE; 120 whereas it affords a considerable impedance to the flow of regular signaling current having a different frequency. In other words, if the propulsion current should induce voltage in the simplex receiving element SE, 125 this current would be shunted away from the condenser 47 in multiple with the amplifying device AS to a large extent, this shunt M, however, allowing very little signaling current to pass therethrough, the signaling 130

current preferably flowing through the condenser in multiple with the amplifying device AS, whereby the potential across this condenser affects the amplifying device AS 5 and in turn energizes the simplex relay S.

The tuning device N comprises an inductance 48 and a condenser 49 connected in multiple which are proportioned to cause resonance at the frequency of the propulsion current, this device being connected in series 10 with the circuit leading from the coils of the loop influence receiving element. Since the condenser 49 and the inductance 48 are connected in multiple, a maximum counter-electro-motive-force is established to the flow 15 of current of a frequency corresponding to that of the propulsion current through the condenser 50, which is provided for the same reason as is condenser 47. The inductance 20 48 and condenser 49, however, are also chosen to permit the flow of signaling current through the device N as freely as possible or practical. In other words, the tuning device N is constructed to form a high impedance 25 to propulsion current and a much lower impedance to signaling current, so that the propulsion current will be entirely, or at least to a large extent, kept out of the condenser 50 in multiple with the amplifying 30 device AL. In order to impress the highest possible voltage on the amplifying device AL, due to signaling current detected by the influence detecting device LE, the capacity of this condenser 50 is such that the voltage 35 drop across this condenser, due to signaling current, is a maximum.

On the vehicle is provided a suitable governor, speed indicating, or speed-responsive device G, which tells the speed at which the 40 vehicle is moving along the trackway. For convenience, this governor has been shown conventionally as comprising a shaft 53 which is driven by the axles of the vehicle in any desired manner, so that its rate of 45 rotation corresponds to that of the axle of the vehicle to which it is connected. On this shaft 53 is provided a collar 54 having ears to which are connected links 55. This collar 54 is pinned to the shaft, as shown, and 50 therefore the position of this collar is fixed.

Another collar 56, having a peripheral groove, is slidably supported on the shaft 53, and is provided with ears to which are pivotally secured links 57, which have their 55 free ends pivotally connected to weights 58, the links 57 being pivotally connected to the same weights. Between the collars 54 and 56 and around the shaft 53 is a compression coil spring 59. The rotation of the shaft 53 causes the weights 58 to separate, due to 60 centrifugal force, thereby causing the collar 56 to be moved downwardly in proportion to the speed of the shaft and consequently the speed of the vehicle. Suitably pivotally 65 supported, as by a pin 60, is a speed indicat-

ing arm 61 which has one end engaging the peripheral groove of the collar 56. The other end of this speed arm 61 is adapted to contact with one or more of the contact segments 62, 63 and 64, depending on the speed 70 of the vehicle.

The train control system, as illustrated in Fig. 1, contemplates the requirement of restriction in the speed of the vehicle, and the operation of a suitable manually operable 75 device in response to a change of traffic conditions ahead of the vehicle. In order to enforce such a restriction in the speed and such manual operation, a suitable electro-pneumatic device EPV is preferably employed. The device EPV preferably acts directly on the air-brake system of the vehicle and applies the brakes if the heretofore mentioned requirements are not carried out, and its construction depends somewhat upon the 80 particular type of air-brake system employed. The most common type of air-brake system is one in which the brake pipe is normally maintained at a predetermined pressure, and in which the brakes are applied 85 if the brake pipe pressure is reduced for any reason, so that the venting of the brake pipe causes an automatic brake application. This device EPV is, therefore, preferably constructed so that if its coil is energized it is 90 maintained in its inactive or ineffective condition, and so that deenergization of its winding effects venting of the brake pipe which is preferably discontinued when the 95 brake pipe pressure has been reduced to a 100 predetermined extent; and which preferably simultaneously with such venting cuts main reservoir pressure off of the engineer's brake valve, so that the engineer is unable to recharge the brake pipe and thereby prevent 105 the automatic brake application and defeat the purpose for which the train control system is provided.

The manually operable device heretofore mentioned preferably comprises a push button 52 connected in the circuits of the carried equipment in a manner so that it can not be maliciously used to prevent the requirement of a reduction in the speed, or the like, and thereby defeat the purpose of 110 the system and which if properly operated permits the train to proceed.

The contact strips 64, 63 and 62 are preferably of such length that the train may be restricted to a high, a medium and a low 115 permissive speed, which may be assumed to be 60, 40 and 20 miles per hour, respectively.

With the apparatus in its normal condition, as shown, the electro-pneumatic device 120 EPV is energized by current flowing from one terminal B of a suitable source of energy, preferably a battery, through the contacts 65 and 66 of the relays L and S, respectively in their energized position through 125

the contact strip 64, speed indicating arm 61, through the EPV back to the other terminal C of said source. Under this traffic condition, the permissive speed of the vehicle is that enforced by the contact strip 64, which may be considered to be 60 miles per hour. If the simplex relay S is deprived of its energy for any reason, the permissive speed of the vehicle is reduced to 40 miles per hour 10 enforced by the medium speed contact 63. The circuit for maintaining the EPV energized under this condition of the apparatus (relay L energized and relay S deenergized) may readily be traced on the drawing.

15 If now the relay S is again energized and relay L is deenergized for any reason, possibly because there is no loop circuit current flowing ahead of the train, this current either being shunted away from the receiving apparatus by another train ahead or being undetectable because it is fed from the entrance end of a section, causes the low speed limit to be enforced since energy is only supplied to the contact strip 62 under this 20 condition by reason of the circuit which may be readily traced in the drawings, and including the contact of the reset push button 52. If now for any reason both the relays L and S are deenergized, the electro-pneumatic device EPV is deenergized regardless 25 of the speed of the train at the time, because none of the segments 62, 63, 64 are now connected to the terminal B of the source of supply, thus deenergizing the EPV and 30 effecting stopping of the train unless the push button 52 is simultaneously depressed.

35 In order to inform the engineer of the condition of the car-carried apparatus and the permissive speed at which the vehicle 40 may move, and also to inform him of traffic conditions ahead, suitable signals are 45 preferably provided. In the particular construction illustrated, four signal lamps G, Y, W and R have been shown. The signal lamp G, indicating clear, is normally energized through the contacts 67 and 68 of the 50 relays L and S, respectively, the caution lamp Y is energized when the relay L is 55 energized and the relay S is deenergized, thus indicating caution, as readily appears from the drawings. With the relay L deenergized and the relay S energized, the two 60 lamps W and R are connected in series across the source of energy having terminals B and C corresponding to a danger indication; and with both the relays L and S deenergized, the lamp R alone is energized, thus 65 indicating that absolute stoppage of the train will take place unless the engineer takes appropriate action to evidence that he 70 is aware of traffic conditions ahead, which action consists in depressing the push button 52.

75 *Operation of system illustrated in Fig. 1.*—In order to more clearly understand the

system as shown in Fig. 1, let us assume that the block J is occupied and that the relay T¹ is in its deenergized condition, thus putting the signal Z¹ at stop and the signal Z at caution.

80 Let us now assume that the train illustrated by axles 30 and 31 is approaching in the block H with the apparatus in its normal condition, as shown, with the clear signal lamp G energized. With the track relay T¹ deenergized, the front contacts 22¹ and 51¹ assume their lower position so as to deprive both the first section and the latter 85 part of the second section of the block I of simplex current. Also with the track relay 90 deenergized, the second section of the block I has its track feed transferred from the exit end to the entrance end thereof. The net result is the first section of the block I is deprived of simplex circuit current whereas 95 the first part of the second section of the trackway although not entirely deprived of loop circuit current is deprived of that kind of loop circuit current which effects the car-carried apparatus, because the track feed 100 feeds from the rear of the section toward the front, and therefore can not effect the receiving element LE for reasons as heretofore explained, and the second part of the second section is deprived of both loop and simplex circuit current.

105 As the train now moves into the block I, the simplex relay S is deenergized because it is deprived of simplex current, thereby setting up an intermediate speed limit of 40 miles per hour, made effective by the contact 110 segment 63 of the governor G. The train may, therefore, proceed through the first section of the block at the medium speed limit of 40 miles per hour and as soon as it exceeds this speed limit its brakes will be 115 automatically applied because the indicating arm 61 leaves contact segment 63. If now the train reaches the point D simplex current will again be present, thereby energizing the relay S; but the relay L is now deenergized, because there is no loop circuit current flowing in the rails ahead of the train. This causes the speed of the train to be restricted to 20 miles per hour enforced 120 by the short-contact segment 62 of the governor G, thus assuring a reduction in speed to at least 20 miles per hour by the time the train reaches the end of the block I. This assurance is due to the proper selection of 125 the point D, so that a train moving at the rate of 40 mph. at the point D will have its speed reduced to at least 20 miles per hour when it reaches the balancing resistance 28 if the brakes are automatically applied at 130 the point D.

Let us assume that the train continues to move from left to right in the normal direction of traffic, and moves beyond the balancing resistance 28 in the block I. Since the 130

block J is occupied, neither loop nor simplex circuit current is present to energize the car-carried apparatus, so that the relays L and S are both deenergized. With the contacts 65 and 71 of the relays L and S in their lower position, the circuit for applying energy to the contact segment 62 is broken so that the device EPV is deenergized. This would ordinarily apply the 10 brakes of the train and bring the train to a stop before it reaches the end of the block I, or the signal Z¹. There is, however, provided a partial auxiliary circuit which includes the push button contact 52 when in 15 its depressed position, and which may be completed by the engineer if alert to allow the train to proceed. If the engineer is alert, he presses the push button 52 as soon as the relays L and S are both deenergized 20 and the brakes applied, whereupon an auxiliary energizing circuit for the electro-pneumatic valve EPV is established through the back contacts 65 and 71 of the relays L and S and the push button 52 down, permitting 25 release of the brakes and allowing the train to advance at the minimum speed.

As the train moves by the signal Z¹ into the block J its speed is not further restricted, but is maintained at this low speed limit of 30 20 miles per hour. This is because the first section of the trackway in the block J is either entirely deprived of track circuit current (loop circuit current) because the second section is occupied and the relay U¹ 35 (not shown) has cut off the source of current from the first section, or this first section is deprived of loop circuit because this current is shunted away from the train in question by the wheels and axles of the train in the block J, all in accordance with the position 40 at which the train in advance is located in the block J.

In practice, the car-carried apparatus is 45 preferably so constructed that the simplex relay S responds to a rather small flow of current in the two track rails in multiple; whereas the loop circuit relay L responds only to a considerably larger current. This is done in order to prevent the loop circuit 50 relay L from being maintained energized by simplex circuit current flowing in one rail alone. For instance, if the balancing resistance at the exit end of a section were broken at its junction to one of the rails, the simplex 55 circuit current would flow through one rail back to the other balancing resistance. Since this current flows through one rail only, it would be in condition to effect the loop circuit influence receiving element LE, because there is no neutralizing or deenergizing current flowing in the other rail. To 60 explain, with the simplex current equally divided between two rails in multiple, the voltage induced in the coil 36, for instance, of the element LE will be counter-balanced

by the voltage induced in the coil 37, these coils being wound in the opposite direction about the core 32 so that if one of these currents only is present an effect is produced upon the amplifying device AL. 70

If, as heretofore explained, the loop circuit car-carried apparatus is so constructed that it does not respond to the simplex current necessary even though the simplex current flows through one rail only, the loop 75 circuit apparatus will be immune, so to speak, to simplex current. On the other hand, the simplex current apparatus is unable to detect loop circuit current because this current flows from one rail to the other 80 through the axles ahead of the axle 31, and therefore does not reach the simplex element SE.

The flow of propulsion current in the rails, assuming this to be alternating current of a different and probably lower frequency, is unable to affect the simplex relay S in the particular embodiment illustrated because the tuning device M shunts the amplifying apparatus AS, so to speak, by providing a low impedance or current resonated shunt in multiple therewith; whereas unbalanced propulsion current which would have the effect of current flowing in one rail of the track only, would have very little or 90 no effect on the loop circuit amplifier AL and the relay L, because the tuning device N, which is tuned for potential resonance for currents having a frequency like that used for propulsion purpose, acts as a barrier to the flow of current in the circuit leading to this amplifying device AL. 95

The car-carried influence responsive device of the control system embodying this invention, therefore, does not depend for its 105 indication on the phase relation of different currents in the rails of the trackway, but depends on two different currents which are segregated, so to speak, by the car axles, and by reason of the fact that one is too small to 110 cause response of the relay designed to be operated by the other. In other words, the simplex circuit current can not affect the loop circuit element because it is too small in value, and the loop circuit current can not 115 affect the simplex circuit element because the first few axles of the train do not allow this loop circuit current to reach the simplex element.

Modification using two different frequencies.—In the system of train control just described, the same frequency was employed for supplying the various simplex circuits as well as the various track or loop circuits. Under certain adverse conditions, it may be 125 difficult to be able to control the two relays L and S independently by their respective trackway currents, and in such cases it may be desirable to provide suitable more distinctive currents so that the current intend- 130

ed for one will not operate the other of these devices.

In Fig. 2 has been illustrated a three-wire transmission line including the wires 4, supplying current to the various track or loop circuit transformers heretofore described. The various transformers shown correspond to and are used for the same purpose as those heretofore described and have been designated by the same reference characters with the distinctive exponent 5. The current transmitted over the extra wire 78 and one of the wires 4 used as a common return wire is considerably different in frequency from that of the frequency transmitted over the pair of wires 4 and is therefore distinctive. Obviously, if two distinctive signaling frequencies are used in the system as shown in Fig. 1, the car-carried apparatus should be designed to operate properly on the particular frequencies transmitted to its corresponding trackway apparatus. That is, the simplex circuit apparatus carried on the train must be properly tuned to respond to the frequency of the current supplied by the simplex transformers 20°, 29° and 44°; whereas the loop circuit apparatus must be designed for the particular frequency used for the track or loop circuit current supplied by the transformers 5° and 8°.

In order to simplify the illustration, the three-wire two-frequency transmission line and the associated transformers only have been illustrated. The rest of the trackway apparatus and the car-carried apparatus are omitted because they are the same as far as the conventional appearance of these devices is concerned, these car-carried devices, however, being tuned for the particular frequencies with which they are to be used.

Having thus shown and described several specific embodiments of the invention, it is desired to be understood that the specific disclosures have been made for illustrative purposes only, rather than with the view of showing the specific construction preferably employed in practice, and that various modifications, changes and deviations may be made to adapt the invention to any one of the various types of railway systems encountered in practice without departing from the scope or the idea of means underlying the present invention.

What is desired to be secured by Letters Patent of the United States, is:—

1. In an automatic train control system for railroads employing alternating current for propulsion purposes, the combination of a trackway divided into blocks by insulating joints, means for causing the flow of signaling currents in the rails of said blocks in accordance with traffic conditions ahead, said signaling currents being of a different and distinctive frequency from that of said propulsion current, and car-carried appa-

ratus comprising an influence receiving coil in inductive relation with the track rails, an amplifying device, a circuit including said coil connecting said coil and said amplifying device, and filtering means connected in series with said circuit, said filtering means including an inductance and a capacity having electrical constants for effecting substantially an infinite impedance to the flow of current having the same frequency as the propulsion current whereas said filtering means only slightly resists the flow of current of a frequency like that of the signaling currents. 75

2. In an automatic train control system 80 of the continuous inductive type; the combination with car-carried apparatus comprising, one influence receiving means responsive to alternating current of one frequency and consisting of a receiving coil 85 disposed inductively with respect to a track rail on which the train is adapted to move, an alternating current relay, and an amplifying device coupled between said receiving coil and said relay, said one influence receiving means including filtering means functioning to render said one receiving means responsive only to current of said one frequency flowing in the track rail; another influence receiving means responsive to alternating current of a different frequency and consisting of another receiving coil also disposed inductively with respect to a track rail on which the train is moving, another 100 alternating current relay, and another amplifying device coupled between said another receiver and said another relay, said another influence receiving means including filtering means functioning to render said another receiving means responsive only to 105 current of said another frequency; and of trackway means for supplying alternating currents of both of said frequencies under favorable traffic conditions ahead of the train, supplying only alternating current of 110 one of said frequencies if less favorable traffic conditions exist ahead and supplying neither of said alternating currents under dangerous traffic conditions ahead.

3. Car-carried apparatus for automatic 115 train control systems of the continuous inductive type comprising, a single phase electro-responsive device which responds to current of a particular frequency flowing in the usual track circuit ahead of the train, 120 another electro-responsive device responsive only to current of a distinct and different frequency flowing in the track rails in multiple in the rear of the first axle of the train, and speed restricting apparatus for governing 125 the speed of the train controlled by said electro-responsive devices.

4. An automatic train control system of the continuous inductive type comprising, two independent single phase electro-respon- 130

- sive devices maintained energized by two distinct trackway circuits through an intervening air gap, and means for restricting the movement of the train differently if the 5 two devices are energized, if one of these devices only is energized, if the other device only is energized, and if both of these devices are deenergized, respectively.
5. In an automatic train control system of 10 the continuous inductive type for railways having their tracks divided into blocks, the combination of means partly on the vehicle and partly along the trackway and acting through an intervening air gap for maintaining a suitable single phase electro-responsive device on the vehicle energized in response to current flowing down one rail and back through the other in a track circuit, means for controlling the speed of the 15 vehicle and for causing an automatic application of the brakes if the speed of the vehicle is excessive in accordance with the condition of said electro-responsive device, said track circuit having its energy supplied to 20 the exit end and entrance end when the block in advance is unoccupied or occupied, respectively.
6. In an automatic train control system of 25 the continuous inductive type for railways having their tracks divided into blocks, the combination of means partly on the vehicle and partly along the trackway and acting through an intervening air gap for maintaining a suitable single phase electro-responsive device on the vehicle energized in 30 response to current flowing down one rail and back through the other in a track circuit, means for controlling the train in accordance with the condition of said electro- 35 responsive device, said track circuit having its energy supplied to the exit and entrance end when the block in advance is unoccupied and occupied, respectively.
7. Car-carried apparatus for automatic 40 train control systems comprising, electro-responsive means on the vehicle controlled from the track in accordance with traffic conditions ahead, a brake control device, a speed responsive device driven by an axle 45 of the vehicle, means for actuating said brake control device if the speed of the train is excessive or actuating said device regardless of the speed of the vehicle (absolute stop) in accordance with the condition of 50 said electro-responsive means, and manually operable means operable while the vehicle is in motion having an active and an inactive position which if moved to the active position and held there allows the train to proceed 55 regardless of the absolute stop restriction imposed, said manually operable means restricting the movement of the train if it is operated when the absolute stop restriction is not enforced, whereby the engineer 60 will not attempt to permanently lock this 65 manually operable means in its active position.
8. Influence communicating means for automatic train control systems of the continuous inductive type for railway systems using 70 alternating current for propulsion purposes comprising, an influence receiving element mounted on a railway vehicle in inductive relation with a track circuit having signaling current flowing therein, an electro-responsive device operatively connected to said influence receiving element and adapted to be permanently energized in response to current flowing in the trackway circuit, and means connected in a circuit connecting said electro-responsive device and said influence receiving element including an inductance and a condenser which have their electrical constants proportioned so as to tune the circuit to potential resonance for the frequency 75 of the propulsion current but to materially restrict the flow of current having a frequency like that of the signaling current.
9. Car-carried apparatus for automatic 80 train control systems of the continuous inductive type for railway systems using alternating current for propulsion purposes comprising, an alternating current electro-responsive device on the vehicle, an amplifying device connected to said electro-responsive device, a coil in inductive relation with a trackway circuit carrying signaling current for causing the flow of current in a condenser in multiple with the input circuit 85 of said amplifying device, and means connected in series with said coil and with the unit comprising the amplifying device and the condenser in multiple therewith, which serves as a barrier to the flow of current of the frequency of the propulsion current but which readily permits the flow of current of a frequency like that of the signaling current.
10. In an automatic train control system 90 for railroads employing alternating current for propulsion purposes, the combination of a trackway divided into blocks by insulating joints, means for causing the flow of signaling currents in the rails of said blocks in accordance with traffic conditions ahead, 95 said signaling currents being of a different and distinctive frequency from that of said propulsion current, and car-carried apparatus comprising an influence receiving coil in inductive relation with the track rails, an amplifying device, a circuit including said coil connecting said coil and said amplifying device, and filtering means connected in series with said circuit, said filtering means including an inductance and a condenser 100 connected in multiple and having constants so as to be resonated to the frequency of said propulsion current, whereby said filtering means greatly restricts the flow of propulsion current but only slightly restricts the flow 105 110 115 120 125 130

of current of the frequency of the signaling currents.

11. In an automatic train control system for railroads employing alternating current for propulsion purposes, the combination of a trackway divided into blocks by insulating joints, means for causing the flow of signaling currents in the rails of said blocks in accordance with traffic conditions ahead, said signaling currents being of a different and distinctive frequency from that of said propulsion current, and car-carried apparatus comprising an influence receiving coil in inductive relation with the track rails, an amplifying device, a circuit connecting said coil and said amplifying device, and filtering means connected in multiple with said influence receiving coil and said amplifying device, said filtering means including an inductance and a condenser connected in series and having constants so as to be resonated to the frequency of the propulsion current, whereby said amplifying device and said receiving coil are substantially shunted as far as the delivery of alternating current of the frequency of the propulsion current from said receiving coil to said amplifying device is concerned.
12. In an automatic train control system of the continuous inductive type; the combination with car-carried apparatus comprising, one influence receiving means responsive to alternating current of one frequency and consisting of a receiving coil disposed inductively with respect to a track rail on which the train is adapted to move, an alternating current relay, and an amplifying device coupled between said receiving coil and said relay, said one influence receiving means including filtering means functioning to render said one receiving

means responsive only to current of said one frequency flowing in the track rail; another influence receiving means responsive to alternating current of a different frequency and consisting of another receiving coil also disposed inductively with respect to a track rail on which the train is moving, another alternating current relay, and another amplifying device coupled between said another receiver and said another relay, said another influence receiving means including filtering means functioning to render said another receiving means responsive only to current of said another frequency; and of trackway means for supplying alternating currents of both of said frequencies under favorable traffic conditions ahead of the train, and supplying only alternating current of one of said frequencies if less favorable traffic conditions exist ahead.

13. Car-carried apparatus for automatic train control systems, comprising a normally energized brake control device, speed control means for de-energizing said brake control device if the imposed speed restriction of said speed control means is violated, influence communicating means for imposing speed restrictions by said speed control means depending on traffic conditions ahead, and a manually operable device for preventing an automatic brake application which must assume one position continuously so long as certain traffic conditions exist ahead and must assume another position continuously so long as other traffic conditions exist ahead to avoid such brake application, whereby said manually operable device is protected against misuse.

In testimony whereof I hereby affix my signature.

CHARLES F. ESTWICK.
